Primary Examiner—T. Chase Nelson(74) *Attorney, Agent, or Firm*—Morgan, Lewis & Bockius LLP(57) **CLAIM**

The ornamental design for a pneumatic nailing machine, as shown and described.

DESCRIPTION

FIG. 1 is a perspective view of the front, left and top of a pneumatic nailing machine showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The elements shown in broken lines are for illustrative purposes only and form no part of the claimed design.
